CLAIM

The ornamental design for a LED lamp, as shown and described.

DESCRIPTION

FIG. 1 is an elevated front perspective view of a lamp showing my new design;

FIG. 2 is a front elevation view of the lamp of FIG. 1, the opposite side being a mirror image thereof;

FIG. 3 is a side elevation view of the lamp of FIG. 1, the opposite side being a mirror image thereof;

FIG. 4 is a top plan view of the lamp of FIG. 1; and,

FIG. 5 is a bottom plan view of the lamp of FIG. 1.

The claimed ornamental design is shown embodied on an assembly that may be used, for example, as a PAR 30 style lamp. In an illustrative example, the lamp may incorporate an LED light source.
